[57] CLAIM

The ornamental design for a set of icons for the display screen of a video monitor, as shown and described.

DESCRIPTION

FIG. 1 is a front perspective view of a set of icons for the display screen of a video monitor; and

FIG. 2 is a front perspective view of a second embodiment thereof; and,

FIG. 3 is a front perspective view of a third embodiment thereof.

The broken line drawing of a video monitor and the broken line drawing of words in all views and the broken line drawing of the arrows in FIG. 1 are for illustrative purposes only and form no part of the claimed design.

1 Claim, 3 Drawing Sheets

FIG. 1

FIG. 2

FIG. 3
